US00D976843S

(12) **United States Design Patent** (10) **Patent No.:** **US D976,843 S**
(45) **Date of Patent:** **** Jan. 31, 2023**

(54) **TERMINAL**

(71) Applicant: **SHINEI HI-TEC CO., LTD.**, Nagano (JP)

(72) Inventors: **Ken'ichi Kobayashi**, Nagano (JP); **Masami Kobayashi**, Nagano (JP)

(73) Assignee: **SHINEI HI-TEC CO., LTD.**, Nagano (JP)

(**) Term: **15 Years**

(21) Appl. No.: **35/512,669**

(22) Filed: **Apr. 1, 2021**

(80) **Hague Agreement Data**

Int. Filing Date: **Apr. 1, 2021**

Int. Reg. No.: **DM/213612**

Int. Reg. Date: **Apr. 1, 2021**

Int. Reg. Pub. Date: **Oct. 1, 2021**

(30) **Foreign Application Priority Data**

Oct. 2, 2020 (JP) ..... 2020-021182 D

(57) **CLAIM**

The ornamental design for a terminal, as shown and described.

DESCRIPTION

1. Terminal

1.1 : Perspective

1.2 : Front

1.3 : Right

1.4 : Top

Fig. 1.1 is a perspective view of a design of a pressfit terminal; fig. 1.2 is a front view thereof; fig. 1.3 is a right view thereof; fig. 1.4 is a top view thereof; the even broken lines shown in the figures illustrate portions of the pressfit terminal that form no part of the claimed design; the dot-broken line is a boundary between the claimed-part and the non-claimed part; this article is used for electrically connecting between electronic members.

1 Claim, 4 Drawing Sheets
